2 SHEETS—SHEET 2.

UNITED STATES PATENT OFFICE.

SAMUEL HENRY SUMMERSCALES, OF WINNIPEG, MANITOBA, CANADA.

INSULATOR FOR HIGH-TENSION CONDUCTORS.

No. 880,412.

Specification of Letters Patent.

Patented Feb. 25, 1908.

Application filed November 23, 1906. Serial No. 344,705.

To all whom it may concern:

Be it known that I, SAMUEL HENRY SUMMERSCALES, a subject of the King of Great Britain, and a resident of Winnipeg, in the Province of Manitoba and Dominion of Canada, have invented a new and Improved Insulator for High-Tension Conductors, of which the following is a full, clear, and exact description.

10 This invention relates to insulators, and is especially adapted to be used for insulating high tension conductors such as used in electrical transmission.

15 The object of the invention is to produce an insulator having improved means for mounting the conductor and having means for preventing, as far as possible, the leakage which tends to occur in the vicinity of the pole and the insulator.

20 More specifically, the purpose of the invention is to provide an arrangement for virtually increasing the length of the path of leakage from the conductor to the arm, and, further, to provide an arrangement for preventing, as far as possible, the leakage which is enhanced by the presence of water around the insulator in rainy weather.

25 The invention consists in the construction and combination of parts to be more fully described hereinafter and particularly set forth in the claims.

30 Reference is to be had to the accompanying drawings forming a part of this specification, in which similar characters of reference indicate corresponding parts in all the figures.

35 Figure 1 is a side elevation of a portion of an arm provided with an insulator constructed according to this invention; the conductor being shown in cross section; Fig. 2 is a side elevation of an insulator and conductor, the arm being shown in end elevation; Fig. 3 is a plan of the arm and insulator; Fig. 4 is a cross section taken on the line 4—4 of Fig. 3 and illustrating especially the construction of 40 the body of the insulator and the manner of attaching the conductor thereto; Fig. 5 is a cross section on the line 5—5 of Fig. 3 and further illustrating the manner of attaching the conductor to the insulator body and the 45 manner of attaching the insulator body to the arm; Fig. 6 is a perspective of the insulator body; Fig. 7 is a perspective of a shield which constitutes a feature of the invention; Fig. 8 is a perspective of a guard plate which consti- 50

tutes a feature of the invention; and Fig. 9 is a perspective of another guard plate which also constitutes a feature of the invention.

Referring more particularly to the parts, and especially to Figs. 1, 2 and 3, 1 represents the arm or pole upon which the insulator 2 is mounted. This insulator comprises a body 3, of glass, porcelain or similar insulating material; it is of substantially pyramidal form, the apex of the pyramid being cut away so as to form a seat. The manner of attaching this base to the arm is clearly shown in Fig. 4; for this purpose the arm is provided with a block 4 which constitutes a seat upon which the lower face of the insulator rests, as indicated. Upwardly through this block fastening devices or bolts 5 extend, the upper extremities of the said bolts being formed into enlarged screws 6 which are threaded into the base of the insulator body, as shown. As indicated in Fig. 3, the insulator body is elongated in the direction in which the arm extends. On the inclined or end faces 9^a, grooves 7 are provided, which may be two in number as shown. These grooves are formed in a vertical plane and have extensions 8 at their sides which extend downwardly from the inclined side faces 9^b of the insulator body as shown in Fig. 6. On the side faces 9^b, horizontal longitudinally disposed grooves 10 are provided, and these are also preferably two in number, as indicated. These grooves preferably incline upwardly toward the interior of the body as shown in Fig. 5.

At the upper portion of the body 3 a seat 11 is formed for a conductor 12, and the construction of this seat and the manner of attaching the conductor thereupon will be described more fully hereinafter. It will appear, however, that the grooves 7, together with their branches 8, are disposed in vertical planes; that is, they are parallel with the conductors. In these grooves are mounted shields 13 and 14, the shields 13 being of substantially elliptical or oval form, of larger dimension than the shields 14, and disposed in the grooves 7 which are disposed nearest to the conductor. One of these shields 13 is very clearly shown in Fig. 7; in its lower edge a notch 15 is formed which is adapted to be received in the upper groove 7, the side edges 16 of the notch lying in the branches 8 of the groove. The shields 14 are similarly formed

with notches in their lower edges which seat in the outermost of the grooves 7. When these shields 13 and 14 are applied, they present the appearance shown in Fig. 1, where 5 the arm is viewed in side elevation.

The adjacent faces of the shields 13 are provided with inclined upwardly extending grooves 17 which are disposed in the lower portion of the plate or shield as indicated in 10 Fig. 7. At their upper ends these grooves cut into the upper portion of the notch 15, as shown. In their lower edges these grooves 17 are provided with small notches or recesses 18, having inclined upper faces and 15 abrupt rear faces, as shown. Similar grooves 19 are provided in the lower portion of these shields or plates, and the lower edges of these grooves are similarly provided with notches 20 as shown.

20 On the inner faces of the outer shields 14, grooves 21 are provided, which are similar to the grooves 19 just described, and in substantially the same plane therewith. From this arrangement, it will be understood that 25 when the shields are applied to the insulator body, as indicated in Fig. 1, the grooves 17 of the two shields 13 will lie opposite to each other. These grooves afford means for attaching sheds 22. The construction of one 30 of these sheds is shown very clearly in Fig. 8; it consists simply of a plate of substantially rectangular form, having a longitudinally disposed rib or tooth 23 which extends along the under side thereof. These sheds are 35 adapted to be applied with their side edges received in the grooves 17, and are adapted to be passed upwardly until their upper edges are seated in the upper grooves 10. At their outer edges, each of the sheds 22 is provided with a longitudinally disposed rib or 40 tooth 24. It should be understood, also that when the shields are all in position, the grooves 21 will come opposite to each other so as to facilitate the attachment of under-sheds 25. The construction of one of these under-sheds is very clearly shown in Fig. 9; it presents an elongated plate 26 which is provided with a pair of parallel slots 27 which extend into the interior of the plate 45 from the forward edge 28 thereof. On the under side, this under-shed is provided with a longitudinally disposed rib 29 which is similar to the rib 23 referred to above. On its under side, this under-shed is provided with 50 an upwardly projecting apron 30, which simply consists of a downwardly tapered flat plate formed integrally with the plate 26. The upper portion of this plate 30 is of enlarged thickness, as shown, so that the lower 55 portion of the plate presents a reduced fin 31, and adjacent to the point of connection between this fin and the body of the plate, downwardly projecting undercut shoulders 32 are formed. The under-sheds 25 are 60 adapted to be applied as indicated, with the 65

end edges thereof received in the grooves 21; they are then forced inwardly, the slots 27 engaging the grooves 19. The inner edges 28 of the under-sheds eventually seat in the lower grooves 10 of the insulator body. 70 When the sheds 22 are pushed into position in the manner described, the ribs 23 thereof, at their ends, engage in the notches 18. In this connection, attention is called to the fact that the ribs 23 present abrupt rear faces 75 and inclined forward faces, so that when they come into the notches, they prevent the sheds from shifting downwardly from the position in which they are represented; likewise, the ribs 29 at the slots 27 engage the notches 20 of the grooves 19 so as to prevent a downward shifting of the under-sheds. Similar notches are provided in the corresponding grooves 21 of the shields 14. Both faces of the shields 13 and 14 are provided 80 with longitudinally extending horizontal ribs 33, and these ribs are formed with inclined upper faces and substantially horizontal lower faces or shoulders 34. In addition to this, the edges of the shields are formed 85 with grooves 35 which extend continuously around them.

In order to form the seat 11, the insulator body 3 is formed with a longitudinally extending channel or gutter 36 in the upper 90 side thereof, so that two oppositely disposed ribs 37 are formed. These ribs are formed with oppositely disposed grooves 38 which align with each other to receive the conductor 12 in the manner indicated. 100

I provide means for holding the conductor in the notches or recesses 38, for which purpose the upper portion of the insulator body is provided with a bolt 39. The lower portion of this bolt is formed into an enlarged 105 screw 40, which is threaded into the upper portion of the insulator body, and the upper extremity of the bolt projects above the insulator body to receive a nut 41; this nut affords means for attaching a saddle 42 which 110 engages the upper side of the conductor between the ribs 37 and which, by means of the nut 41, may be clamped upon the conductor, as will be readily understood.

The shields 13 and 14 and the sheds and 115 under-sheds are formed of a dielectric material, so that the path of leakage from the conductor 12 must lie around the edges of the shield. In this way, the virtual distance from the conductor to the insulator arm is 120 much increased. By reason of the pyramidal form of the insulator, the water which falls upon the insulator is quickly shed therefrom. By reason of the grooves 35 in the edges of the shields, the water which falls upon the 125 edges of the shields is carried down the edges so that there is a tendency to keep the side faces of the shields free from moisture. The projecting ribs 33 presenting, as they do, the horizontal protected shoulders 34, tend to 130

produce the same desirable result. In this way the faces of the shields are protected, as far as possible, from the accumulation of water, and, furthermore, the shoulders 34 will 5 remain comparatively dry. In this way, it becomes impossible for an unbroken path of leakage to exist along the wetted surfaces of the insulator and shields. The construction of the sheds and under-sheds tends to bring 10 about the same desirable result as that just referred to, and attention is called, also, to the shoulders 32 of the under-sheds which will remain dry. It will be observed, also, that the fins 31 of the under-sheds project 15 downwardly opposite to the metallic bars 1^a and 1^b, of which the insulating arm may be constructed as shown. In this way they operate to increase the length of the path of lines of leakage which can pass around the 20 outer edges of the upper plates 26 of the under-sheds.

Special attention is called to the manner in which the shields and the sheds and under-sheds are mounted on the insulator body, 25 without necessitating the employment of fastening devices of any sort; on account of the construction used, the parts hold themselves in position upon the insulator body.

It should be understood that the plates fit 30 tight in their grooves so as to exclude the water at these points. In this way it becomes impossible for a water film to collect and form a "short circuit" as it were, under the edge of a plate. If it is not feasible to form 35 water-tight joints as suggested, this may be accomplished by any well known method such as by applying a coating of water-proofing material or cement.

Having thus described my invention, I 40 claim as new and desire to secure by Letters Patent:

1. An insulator presenting a body adapted to be mounted upon a support, and having shields disposed on opposite sides of the conductor, said shields being formed of dielectric material whereby the length of the path of leakage in the direction of said shields to 45 the support is increased.

2. An insulator having a body adapted to 50 be mounted upon a support, and shields attached to said body in the path of lines of leakage which might pass to said support, said shields having projecting portions adapted to prevent the formation of a continuous coating of water on said shields.

3. An insulator having a body adapted to 55 be mounted upon a support, shields mounted upon said body on opposite sides of the conductor and presenting ribs extending longitudinally thereof, said ribs presenting protected under faces adapted to prevent the accumulation of water, and sheds disposed between said shields.

4. An insulator having a body adapted to 60 be mounted upon a support, and having sub-

stantially parallel shields of dielectric material mounted thereupon, and sheds adapted to interlock with said shields, said sheds and said shields being adapted to intercept the lines of leakage from the conductor to 7 the said support.

5. An insulator having a body adapted to be mounted upon a support and presenting a substantially pyramidal form with grooves in the faces thereof, shields attached in said 75 grooves and adapted to intercept leakage currents passing across them toward said support.

6. An insulator having a body of substantially pyramidal form adapted to be 80 mounted upon a support and presenting grooves in the faces thereof, shields mounted in said grooves and adapted to intercept leakage currents passing from said conductor to said support, said shields being 85 disposed in substantially parallel relation, and sheds and under-sheds disposed between said shields and intercepting leakage currents tending to pass on the surface of said body longitudinally with respect to said 90 conductor toward said support.

7. An insulator having a body of substantially pyramidal form adapted to be mounted upon a support and presenting grooves in the faces thereof, shields mounted 95 in said grooves and adapted to intercept leakage currents passing from said conductor to said support, said shields being disposed in substantially parallel relation, sheds and under-sheds disposed between 100 said shields and intercepting leakage currents tending to pass on the surface of said body longitudinally with respect to said conductor toward said support, said under-sheds having downwardly projecting aprons 105 disposed opposite the said support whereby leakage to said support is prevented around the lower edges of said under-sheds.

8. An insulator having a body adapted to be mounted upon a support, shields mounted 110 upon said body substantially parallel with the direction in which the conductor extends, under-sheds attached between said shields and having downwardly extending aprons disposed opposite said support, said 115 under-sheds being adapted to prevent the leakage currents passing across the surface of said body longitudinally with respect to said conductor, said shields being adapted to prevent the leakage of currents passing 120 across the surface of said body laterally from said conductor.

9. An insulator having a substantially pyramidal body adapted to seat upon a support, said body having grooves in the faces 125 thereof, shields mounted in said grooves and disposed substantially parallel with the conductor, said shields being arranged in an upper pair and a lower pair, the upper pair of shields having grooves on their adjacent 130

faces, sheds received in said grooves and engaging said body at the upper edges thereof, the lower pair of said shields having grooves on their adjacent faces, under-sheds engaging said last grooves, said sheds and under-sheds being adapted to cut off leakage currents passing across the surface of said body longitudinally with respect to said conductor, said shields being adapted to cut off

leakage currents passing across the surface 10 of said body laterally from said conductor.

In testimony whereof I have signed my name to this specification in the presence of two subscribing witnesses.

SAMUEL HENRY SUMMERSCALES.
